UNITED STATES PATENT OFFICE.

FRANCIS E. ASHTON, OF EXETER, NEW HAMPSHIRE, ASSIGNEE TO CROMPTON &
KNOWLES LOOM WORKS, A CORPORATION OF MASSACHUSETTS.

WEFT-REPLENISHING LOOM.

961,668.

Specification of Letters Patent. Patented June 14, 1910.

Application filed November 18, 1909. Serial No. 528,673.

To all whom it may concern:

Be it known that I, FRANCIS E. ASHTON, a citizen of the United States, residing at Exeter, in the county of Rockingham and State of New Hampshire, have invented certain new and useful Improvements in Weft-Replenishing Looms, of which the following is a specification.

My invention relates to weft replenishing looms, and more particularly to the magazine of a weft replenishing loom for holding the bobbins or filling carriers.

Magazines for weft replenishing looms, as ordinarily made, are of the stationary type, or the movable type. Magazines of the movable type ordinarily have a rotary motion in the arc of a circle, the axis of which is in a horizontal plane.

The object of my invention is to improve upon the construction of rotary magazines, and more particularly to provide a rotary magazine for two or more sets of bobbins or filling carriers, which has a rotary movement in the arc of a circle, the axis of which is in a vertical plane, and the bobbins are moved in a horizontal plane, at predetermined intervals, and each set of bobbins carried over the shuttle at the stationary end of the loom, preparatory to supplying a fresh bobbin for the substantially exhausted bobbin in the running shuttle.

My invention consists in certain novel features of construction of my improvements as will be hereinafter fully described.

I have only shown in the drawings a detached portion of a weft replenishing loom, and particularly the magazine portion of the loom, embodying my improvements, sufficient to enable those skilled in the art to understand the construction and operation thereof.

Referring to the drawings:—Figure 1 is a side view of a detached portion of the right hand end of a weft replenishing loom, and my improved magazine combined therewith; the magazine is shown in section, on line 1, Fig. 2, looking in the direction of arrow *c*, same figure. Fig. 2 is a plan view of the magazine, and some of the parts shown in Fig. 1, looking in the direction of arrow *b*, same figure. Fig. 3 shows, on an enlarged scale, a detached lower portion of a compartment or guide-way, shown in Fig. 1. Fig. 4 corresponds to Fig. 3, but shows some of the parts in a different position. Fig. 5

shows, on an enlarged scale, the front view of a guide-way for the tip of the bobbins, with the thread holder detached, looking in the direction of arrow *c*, Fig. 2, and, Fig. 6 corresponds to Fig. 1, but shows a modified construction of the magazine, with the trans-ferrer arm located within the central part of the magazine.

In the accompanying drawings, 1 is a portion of the loom side or end frame, 2 the loom arch, 3 the breast beam, 4 the lay, and 5 the shuttle. On the front of the lay is the dagger 6, adapted to engage the end of a bunter 7, carried on the downwardly extending arm 8' on the hub 8" of the trans-ferrer arm 8 carrying the trans-ferrer 8'', see Fig. 2, when through arm 9, link 9', and arm 10 connected with the filling detecting mechanism, upon the practical or substantial exhaustion of the filling on the bobbin in the running shuttle, the bunter 7 is raised into the path of the dagger 6, to operate the trans-ferrer arm 8, in the usual and well known way.

I will now describe my improvements in the revolving magazine.

A stand 11 is secured to the loom side 1, and to the arch 2, and has in this instance fastened thereon a bracket or stand 12, on which is a boss 12', in which is secured the upper end of a vertically extending rod 13. Loosely mounted on the rod 13, and held thereon by a nut 14, is a vertically extending sleeve 15. Each end of the sleeve 15 is provided with arms 15', in this instance four in number, which extend out therefrom, and to the ends of said arms are secured vertically extending compartments 16, having guide-ways 16' for the butts, and 16'' for the tips of the bobbins 17. Combined with the guide-ways 16' for the butts of the bobbins, near the lower discharging end thereof, is a movable bobbin holder or support 19, shown on an enlarged scale in Figs. 3 and 4, having a hub 19', which is pivotally mounted on a stud 20 secured to a boss 20' on the compartments 16. The inner end of the support 19 carries in this instance two outwardly extending pins or wires 21, and 21', see Figs. 3, and 4, which are of sufficient length to support a bobbin 17. The lower pin 21 is adapted to extend under the lowest bobbin, as shown in Fig. 4, to retain all of the bobbins in a compartment in position, during the normal operation of the loom.

An arm 19" extends outwardly from the hub 19' and is adapted to be engaged by the transferrer arm 10 upon its upward movement, to rock said arm 19", against the action of a torsion spring 22 encircling the stud 20 and secured to it at one end, and engaging the arm 19" at its other end, to release the lowest bobbin, and allow it to drop to the discharging end. The upper pin 21' will be moved into position to hold the next bobbin, in its descent by gravity in the compartment, as shown in Fig. 3, until the transferrer arm moves downwardly to transfer the bobbin at the lower end of the compartment. The lowest bobbin in a series, which is dropped to the discharging end, rests upon extensions 23' on two vertically extending levers 23, which are pivotally mounted on studs 24 on the enlarged head 25' on the vertically moving rod 25. The rod 25 is suitably guided in a guide-way 16'" on the inner part of the guide way 16' for the butt of the bobbin and is provided with a collar 25''. A helically coiled expansion spring 26 encircles the rod 25, and engages at one end the collar 25'', and at its other end the lower end of the guide-way 16''' in the guide-way 16', and acts to move upwardly said rod 25 and the levers 23 thereon. The upwardly extending arms of the levers 23 are rounded, at 23'', and engage the enlarged portion 16a on the guide-way 16''' in the normal operation of the loom, to hold the lower ends of the supports 23 in their closed position to support a bobbin 17, as shown in Fig. 3. The engagement of the transferrer 8" with the bobbin, as shown in Fig. 4, will move down the supports 23 carried on the vertically moving rod 25, against the action of the spring 26, until the rounded ends 23'' on the supports 23 pass on to the reduced end portion on the part 16''', to allow the supports 23 to move apart at their lower ends, to release the bobbin, as shown in Fig. 4.

The devices for holding the tips of the bobbin, are the same as the devices for holding the butts of the bobbins, above described.

The holder for the ends of the filling threads from the bobbins, in this instance consists of upwardly extending wires, suitably attached to each compartment 16, as shown in Fig. 5 extending in a substantially vertical direction. One wire 27 is preferably covered with felt or other friction material, and the other wire 28 is attached to the first mentioned wire, leaving a space between them to receive and hold the filling threads, preferably in bunches, see Fig. 1, which work downwardly, as the bobbins drop into their compartments. If one of the compartments in the magazine is emptied, the operator turns the magazine by hand to the next compartment, and to hold the maga-

zine in position, while the loom is in operation, I provide in this instance a pivotal lever 29, see Fig. 2, which carries a roll 30, which enters a recess 31' in a disk 31 secured to the sleeve 15. A helically coiled contraction spring 32 is attached at one end to said lever 29, and at its other end to the stand 12, and acts to yieldingly hold the roll 30 in engagement with the recess 31' in the disk 31. 75

In Fig. 6 is shown a modified construction of my improvements, in which the transferrer arm 8 is located within the central portion of the magazine. A stand 33 is in this instance secured at its lower end to the loom side or end frame 1, and has secured thereto an upright bracket 34 for the vertically extending rod 13. The transferrer arm 10 has its hub pivotally mounted on stud 35, carried on the downwardly extending arms 34' on the bracket 34. 85

My improved rotary magazine, as shown in the drawings, may be turned by the operator to bring each set of bobbins over the shuttle at the magazine end of the loom, in which case all of the bobbins would preferably have filling thereon of the same color. In case it was desired to use bobbins having different colored filling thereon, then the magazine could be connected with the shifting shuttle boxes at the other end of the loom, to be operated automatically in the usual way by the shifting of the shuttle boxes, or could be connected with a supplemental pattern surface, to be moved at predetermined intervals by said pattern surface, as will be well understood by those skilled in the art. 95

It will be understood that the details of construction of my improvements may be varied if desired. 105

Having thus described my invention, what I claim as new and desire to secure by Letters Patent is:—

1. In a weft replenishing loom, a magazine for a plurality of sets of bobbins or filling carriers, having a rotary movement in a substantially horizontal plane, and means for rotating the magazine about a substantially vertical axis. 110

2. In a weft replenishing loom, a magazine for a plurality of sets of bobbins or filling carriers, having its axis of rotary movement in a substantially vertical plane, and means for rotating the magazine about its axis. 115

3. In a weft replenishing loom, a magazine for a plurality of sets of bobbins or filling carriers, which extend in a substantially horizontal plane, said magazine having a rotary movement in a substantially horizontal plane, and means for rotating said magazine about a substantially vertical axis. 120

4. In a weft replenishing loom, a magazine for a plurality of sets of bobbins or fill- 125

ing carriers, having vertically extending compartments or guide-ways, adapted to be moved on a substantially vertical axis.

5. In a weft replenishing loom, a magazine for a plurality of sets of bobbins or filling carriers, having vertically extending compartments or guide-ways, adapted to be moved on a substantially vertical axis, and a transerrer adapted to transfer the lowest 10 bobbin in anyone of the compartments into the running shuttle.

6. In a magazine for a weft replenishing loom having a compartment for a plurality

of bobbins, and a support for each compartment for the bobbin next to be transferred is into the running shuttle, and means for moving said support in the direction of the shuttle with the bobbin, preparatory to the bobbin being transferred into the shuttle, and a second support for the bobbin above the one next to be transferred.

FRANCIS E. ASHTON.
